UNITED STATES PATENT OFFICE.

JOHN S. SANGER, OF ORANGE, NEW JERSEY.

DESIGN FOR A TOOTH-POWDER HOLDER.

SPECIFICATION forming part of Design No. 23,963, dated January 29, 1895.

Application filed October 29, 1894. Serial No. 527,349. Term of patent 7 years.

To all whom it may concern:

Be it known that I, JOHN S. SANGER, a citizen of the United States, residing at Orange, Essex county, New Jersey, have invented a certain new and useful Design for Tooth-Powder Holders, fully described and represented in the following specification and the accompanying drawing, forming a part of the same.

10 This design consists in a novel shape for a tooth powder holder.

The annexed drawing exhibits a perspective view of such tooth powder holder.

15 The design includes the form of the receptacle and the frame for supporting the same. The receptacle *d*, including the cover *e*, is of rectangular shape with all the corners heavily rounded. The frame comprises a band *a* en-

circling the receptacle and having outwardly spreading legs *b* with intermediate ties *c* near the bottom.

The essential features of the design are the form of the receptacle and its supporting frame, substantially as shown in the drawing.

Having thus set forth the nature of my design, what I claim as my invention, is—

The design for a tooth powder holder, herein shown and described.

In testimony whereof I have hereunto set my hand in the presence of two subscribing witnesses.

JOHN S. SANGER.

Witnesses:

L. LEE,
THOMAS S. CRANE.
